JOHN L. PERKINS, OF HOLYOKE, MASSACHUSETTS, ASSIGNOR TO B. F. PERKINS AND SON, INCORPORATED, OF HOLYOKE, MASSACHUSETTS, A CORPORATION OF MASSACHUSETTS.

STRENGTH-TESTING APPARATUS.

No. 924,579.

Specification of Letters Patent.

Patented June 8, 1909.

Application filed August 21, 1908. Serial No. 449,672.

To all whom it may concern:

Be it known that I, JOHN L. PERKINS, a citizen of the United States of America, and resident of Holyoke, in the county of Hampden and State of Massachusetts, have invented certain new and useful Improvements in Strength-Testing Apparatuses, of which the following is a full, clear, and exact description.

10 This invention relates to apparatus for testing the tensile strength of sheet materials, such for instance as paper; and the apparatus comprises a base or support having a cylindrical liquid containing bore 15 therein, a piston in the bore and means for endwise moving it against the liquid, another piston in the bore, in resistance against the liquid subjected to pressure by the first piston and also endwise movable when a breaking pressure or strain is attained, said second piston having a stem longitudinally extended to the exterior of the bore provided base, a pair of clamps for confining end portions of the sheet material, one of which is 20 fixed and the other longitudinally movable, and also oscillatory by reason of having a link-connection with the aforesaid extended piston stem, and a pressure gage connected with the said bore for indicating the maximum pressure to which the liquid is subjected as a medium of transmission of the force exerted between the two pistons.

The machine or apparatus is illustrated in the accompanying drawings in which:—

35 Figure 1 is a substantially central vertical longitudinal section,—the pressure gage or indicator and a portion of the link being shown in front elevation with parts broken away to disclose the internal construction.

40 Fig. 2 is a plan view of the apparatus,—the gage being omitted. Fig. 3 is a vertical cross sectional view on line 3—3, Fig. 1.

Similar characters of reference indicate corresponding parts in all of the views.

45 In the drawings, A represents the body or stationary base of the apparatus having a cylindrical bore B of uniform diameter from end to end therethrough.

a and b represent annular bushing plugs 50 screw engaged in the end portions of the bored base; and within the bore are pistons C and D,—provided with cup-leathers or hydraulic packings e,—and arranged in suitable separation to give space for occupancy 55 between them of a body of liquid, such, for

instance, as glycerin, indicated at x. From a space between the pistons a passage f rearwardly and upwardly leads, and with which the pressure gage E is connected. A portion of the length of the piston C is made 60 tubular and internally screw threaded and receives engagement therewithin of the screw threaded inner portion of a shaft F which is rotatably fitted through the annular bushing plug a but rendered endwise immovable by the abutment of the shoulders g, g², which are provided thereto, against the inner and outer ends of the bushing plate. The shaft has at its outer extremity a fixed hand wheel G for conveniently turning the shaft F and securing thereby an endwise forcing movement of the piston C against the body of liquid x. The other piston D has a stem H longitudinally extended to the exterior of the base in which 70 the bore B is provided at the opposite end from the location of the shaft F,—its extremity being guided through a circularly apertured bracket arm h and provided with a knob or shoulder i which by abutment 75 against the left hand face of the bracket limits the movement of the piston D toward the one C and is determinative of the normal position of the piston D while the endwise abutment at the right of the piston C against 80 the shoulder g of the screw shaft F is determinative of the normal position of the piston C.

J and K represent clamps for holding the ends of the paper or other sheet strip or cord-like material to be tested by a pulling strain thereon. One of the clamps is fixed and the other is movable by being connected with the stem H of the piston D. Each clamp comprises a base platform-like member or plate 90 10 and a superimposed movable gripping plate 12 having perforations vertically therethrough through which headed studs 13, screw engaged or otherwise anchored in the base members, are loosely extended, the heads of 100 such studs limiting the extent of separating movements which the upper clamp plates may have relatively to their fellow members by reason of the interposed and upwardly reacting springs 14 accommodated in counter-sunk cavities therefor in the paired plates 10 and 12, as shown. The skeletonized upper clamp plates 12 permit risers or ear lugs 15, 15, to be extended as integral members 105 of the lower clamp plates considerably above 110

the upper ones, and cam ended levers *m* pivoted between and supported by said ear lugs exert each a pressure upon the proximate upper clamp plate to force it practically against the lower one, to bind the paper, and to securely hold it during the testing operation.

In the drawings, a strip of paper to be tested is represented at *y* in all of the views.

- 10 The lower plate or platform-like portion of the movable clamp *K* is constituted by the end portion of a link *N*, the left hand or farther end of which is apertured and engaged over a portion *17*, which is of reduced diameter of a stud or bar *O* which is pinned or otherwise affixed to an intermediate portion of the plunger stem *H*,—said bar below its portion which embraces the piston stem engaging in a slot *n* in a horizontal member 20 of the aforementioned bracket *h* whereby the stud *O* is maintained with double assurance in its vertical position without impediment to its reciprocation as an adjunct of the piston and its stem.
- 20 25 The gage or indicator *E* is, in no material composition, different from an ordinary steam gage or gage such as has been heretofore used in other descriptions of paper testing machines, but the same will be herein briefly described for the purpose of rendering manifest the feasibility of this apparatus as a whole.

The pressure gage comprises a shell or casing *p* provided with a tubular plug 22 connected with the liquid passage *f* heretofore referred to as having connection with the portion of the cylindrical bore *B* in which the liquid *x* is contained. The passage in the tubular plug is continued in a curved tube 23, the outer or free end of which is closed and which tube is capable of springing under the pressure of liquid forced thereto to a less extremely or sharply curved condition. The gage has a graduated face dial 25 over which an index finger or needle 26 is movable, from the normal or zero position variably to the maximum, according to the pressure to which the liquid is subjected by the forcible movement of the one piston *C* relatively to the other one *D*. The needle is carried on an arbor 27 having a pinion 28 with which meshes the sector gear 29 on an intermediately pivoted lever 30 provided with an upstanding stud 31. An arm 32 having a hooked end engages the stud 31 and swings the lever and moves the needle 26 in extent proportionate to the pressure to which the liquid is subjected and to the strengthening movement of the spring tube 23.

The sheet of paper being clamped while the parts of the apparatus are in their normal positions, and the screw *F* rotated through the hand wheel *G*, a pressure will be imparted against the liquid at *x* which will be

resisted by the clamped paper which restrains the piston *D* against movement, initially; the pressure to which the liquid is subjected will be absorbed in the spring tube 23 and cause a movement around the face of the graduated dial of the needle 26 up to the time when the pressure becomes so great as to break the paper, whereupon because of such breakage the piston *D* and clamp *K* therewith connected will have more or less 75 movement away from the location of the other clamp *J*. So soon as the paper becomes severed by the pulling strain imposed thereon, the deflection of the tubular spring 23 not only ceases but such spring recoils to 80 its normal position shown, leaving the sector ended lever in the position to which it had been swung and the needle remaining in registry with the graduation on the dial indicating the number of pounds pressure at 85 which the paper had been fractured. Under these conditions the end of the lever carrying the stud 31 will be somewhat above and away from the hook end of the bar 32 which will have returned to its normal position. 90 After an interval sufficient for the inspection of the gage to perceive under what force a given strip of paper had been broken by the pulling strain, to which it had been subjected, and in order to restore the gage with its 95 sector lever in its normal position of Fig. 1, and the needle again at zero, the stud 34 is inwardly pushed against an angular arm 35 of the sector lever and against its spring 36, which on the release of the finger pressure 100 for the restoring of the parts outwardly reacts again to place the inner end of the stud 34 free and clear from the arm 35 of the sector lever so as not to in any way impede the next action of the gage. 105

By making the clamp *K* as an extremity of the pivoted bar or link *N*, in case the strip of paper is not of uniform width, or is not accurately clamped in the devices *J* and *K*, a rectification will be effected in the line of strain on the paper so that it will be in the truly general longitudinal line or "median" of the strip precluding any tendency which might otherwise exist of a twisting or tearing strain on the strip, but on the other hand assuring always a purely pulling or tensile strain. 110 115

I claim:

1. In an apparatus of the character described, a base or support having a cylindrical horizontal longitudinally extending liquid-containing bore therein, a piston in the bore, a portion of which is tubular and internally screw threaded, a shaft, restrained against endwise movement but rotatably 120 fitted through an end portion of the base in line with, and screw engaging, said piston, and having a hand-wheel for rotating it, another piston in the bore, in resistance against the liquid subjected to pressure by 125 130

- the first piston and also endwise movable, having a stem extended beyond the other end portion of the base, a pair of clamps for confining end portions of the sheet material, 5 one of which is fixed and the other connected with said piston stem and longitudinally movable in unison therewith, and a pressure gage connected with the portion of the bore between the pistons.
- 10 2. In an apparatus of the character described, a base or support having a horizontal cylindrical bore extending from end to end therethrough, annular screw plugs engaged in each end of the bore, a piston within one 15 end portion of the bore, a portion of which is tubular and internally screw threaded, a shaft, a portion of which is rotatably fitted in one of said annular screw plugs, the inner end portion thereof being threaded and screw 20 engaging said piston, and having shoulders in engagement against the inner and out faces of the screw plug, and also having a hand wheel at its outer end, another piston in the bore having a stem longitudinally ex- 25 tended through and beyond the screw plug at the other end of the base and provided with an upstanding stud, a pair of clamps one stationary upon the top of the base and the other movable on the top of the base and 30 having a connection with said stud and a body of liquid in the intermediate portion of the bore between said pistons and a pressure gage connected with the liquid containing portion of the bore.
- 35 3. In an apparatus of the character described, a base or support having a flat top and having a cylindrical longitudinally extending liquid containing bore therein, a piston in the bore and means for endwise mov- 40 ing it, another piston in the bore having a stem longitudinally extended to the exterior of the base, a clamp in a fixed position on the top of the base comprising a base plate and a separable superimposed plate, springs oper- 45 ative to force the plate apart and a cam lever for forcing the one plate against the other, another clamp slidably supported on the top base comprising a base plate constituted by an extremity of a bar or link having a piv- 50 otal connection with the stem of the second named piston and having a superimposed plate with interposed separating springs and a cam lever for crowding the clamp members together, and a pressure gage connected with the portion of the bore between the pistons. 55
4. In an apparatus of the character de- 60 scribed, a base or main elongated horizontal support having a cylindrical bore there- through, separated pistons in said bore with a body of liquid therebetween, one of said pistons having a stem extending endwise be- 65 yond the base, a bracket at the end of the base comprising a horizontal member with a longitudinal upwardly opening groove there- in and a vertical member through which said stem plays, a knob at the end of the stem outside of the bracket, a bar embracing and secured to the stem having a depending member slidably guided in said groove and having an upstanding stud, a bar having one 70 end pivotally engaged with said stud and having its other extremity supported on the flat top of the base and comprised in a mov- 75 able paper clamp, another paper clamp in a fixed position at a further portion on the top of the base, a pressure gage connected with the liquid containing portion of the said bore, and means for endwise moving the piston which is opposed to the said stem provided 80 piston.
5. In an apparatus of the character de- 85 scribed, the combination with a base having a cylindrical bore therethrough, and having a conduit leading rearwardly and upwardly from an intermediate portion of said bore, 90 pistons in separated relations within said bore, one thereof having in conjunction therewith means for endwise forcibly moving it and the other having a stem extended endwise beyond the end of the base, a sta- 95 tionary clamp on the top of the base and a movable clamp on the top of the base, and a connection between the movable clamp and said piston stem, a pressure gage comprising a tubular plug connected with said conduit, and a body of liquid in the bore between the pistons and communicating through said conduit with the gage.
